UNITED STATES PATENT OFFICE

THOMAS J. OSINGA, OF CHICAGO, ILLINOIS

FASCIA PLATE INSTALLATION

Application filed January 21, 1930. Serial No. 422,472.

My invention relates to elevator shaft installations, and more particularly to the covering of the area between the sill and the door-hanger enclosures, and my main object is to provide a covering of this kind which presents a smooth and neat appearance.

A further object of the invention is to provide a simple retaining device for the lower portion of the fascia plate entering into the installation, whereby to eliminate screws or other fastening devices.

A still further object of the invention is to provide a retainer of the character mentioned which serves its purpose whatever the height of the fascia plate may be.

Another object of the invention is to design the sill with novel means to retain the fascia plate without the need of accuracy in the height of the same.

An additional object of the invention is to provide fastening means for the fascia plate which are located beyond the lateral limits of the elevator cab opening and therefore invisible to persons riding in the cab.

A significant object of the invention is to extend the retainer above referred to with means to secure a firm support from the header of the door-hanger enclosure and also means to support the cover plate of the latter.

A secondary object of the invention is to provide modified expedients for the installation peculiar to the upper and lower limits of the elevator shaft.

A final but nevertheless important object of the invention is to design the installation with parts of extreme simplicity and durability, making attention or repair unnecessary or very infrequent.

With the above objects in view and any others that may suggest themselves from the specification and claims to follow, a better understanding of the invention may be had by reference to the accompanying drawings, in which—

Figure 1 is an elevation of the covering installation as viewed from within the elevator shaft, the dotted lines A and B representing the lateral limits of the elevator cab opening;

Fig. 2 is an enlarged section taken on the

line 2—2 of Figure 1, and showing the parts in full size, except for a portion broken away;

Figs. 3 and 4 are views similar to Figure 1, denoting respectively installations at the top and the bottom of the elevator shaft to include modifications of the invention;

Figs. 5 and 6 are, respectively, sections on the lines 5—5 and 6—6 of Figures 3 and 4; and

Figs. 7 and 8 are perspective views of details involved in the modification of Figures 3 and 5.

The space between a floor and the ceiling below where an installation of elevators is located is usually occupied by sill supporting and regular layers of masonry 5 and 6, as indicated in Figure 2, the layer 6 being set back to provide space 7 in which the door hanger housing 8 is fitted. The sill 9 for the landing door 8^a above is installed over the masonry layer 5, and the door hanger enclosure 8 is formed with a top header plate 10 which projects forward into the zone of the fascia plate 11. The dotted line C in Figure 2 represents the frontal line of the elevator cab course.

With reference to the door hanger enclosure 8, I have illustrated within the same a hanger patented by me on April 16, 1929, under Number 1,709,279, although any type of hanger may be installed, the present invention having no direct connection with the type of hanger. In the hanger installation shown, the header plate 10 carries projected brackets 12 against which is placed the cover 13 for the door-hanger enclosure. In order to support the cover 13, I form the header plate 10 with a vertical frontal bend 10^a over which I fit a plate 14 of inverted U-shape, the frontal portion of this plate extending downwardly and terminating in an inward U-hook 14^a. The cover 13 is formed with an outward U-hook 13^a which is adapted to be hung in the hook 14^a of the plate 14 and to thus receive its support.

The rear section 14^b of the plate 14 extends downwardly to the angle of the header plate, then takes a rearward bend 14^c upon the latter, and finally an oblique bend 14^d

14d in a frontal direction, the bend 14d terminating at approximately the height of the plate 14 with a rearward curve or bead 14e. The one piece structure of the plate 14, as just described, is of heavy sheet metal and so formed that the bend 14d exerts an inherent pressure against the inner portion 14d of the plate 14.

10 The structure of the plate 14 is for purposes of facility assembled with the header plate 10 before the latter is installed in the masonry. While the plate 14 may be snugly assembled with the header plate without any additional fastening, it is expedient to apply screws 15 upwardly from the header plate into the base 14c of the plate 14 before the cover 13 is hung in place, so that the units may be considered as secured against separation or lateral deviation. It will be observed at this time that the screws 15 are in a secluded position and invisible from the elevator shaft.

15 Heretofore the method of securing the fascia plate 11 to the header plate 10 and to the sill 9 above has been largely a matter of ordinary application. In other words, the fascia plate would be secured above and below by screws or fastening means, and such fastening means as well as the lines of the joints would be open to the view of elevator passengers and suggestive of unsightly patchwork. In fine buildings, it is essential that neatness of elevator design be extended as far as possible to the surroundings. Thus, 20 an unsightly cover between floors is repeatedly visible to the passengers as they face the doors during the travel of the elevator from floor to floor, and it is therefore imperative to improve this immediate item in order not to have it detract from the appearance of the elevator. Accordingly, I designed the fascia plate 11 without any securing means which are visible from the elevator cab. To install the plate, I tilt it slightly with the lower end in a rearward direction to facilitate the entry of such end into the space between the sections 14b and 14d of the plate 14, lowering the plate to a point near the base 14c, as indicated by dotted lines in Figure 2. 25 Above, I slot the frontal portion of the sill 9 as indicated at 9a in an upward direction with sufficient room to slidably receive the upper portion of the fascia plate, the inner wall of the slot being extended downwardly as indicated at 9b to form a backing for the fascia plate as shown. The extension 9b may be continuous across the length of the sill, or it may be made only in certain places. These places receive tapped bores 9c made in the extension to receive screws 16 directed through horizontal slots 11a made near the upper end of the fascia plate.

30 In installing the fascia plate according to the dotted lines in Figure 2, its upper ends will be brought sufficiently low to clear the

entrance to the slot 9a. Then the plate may be raised to enter the slot more fully and to such a height as to place the plate slots 11a even with the tapped bores 9c of the sill extension 9b to facilitate the application of the screws 16. As noted in Figure 1, the covering installation is of a width sufficient to amply extend beyond the elevator door opening, and the fastening means involving the screws 16 are placed a sufficient distance beyond the limits of such opening as to be entirely invisible to the passengers of the elevator.

35 The slotted portion of the sill 9 is frontally identified by a rounded molding 9d which 80 gracefully meets the surface of the fascia plate. Likewise the rounded upper and lower portions of the retaining plate 14 also make a neat and finished front for the covering installation being more suggestive of 85 an ornamental molding than of a mechanical element. Thus, to the elevator passengers, only the flat and smooth effects of the sill molding 9d, the fascia plate 11, the retaining plate 14 and the cover 13 are apparent, 90 completing the neatness of the modern elevator design.

40 Mechanically considered, the structure of 95 offers first a simple support for the cover plate 13, permitting the latter to be unhooked instantly for removal. Further, the curved upper portion of the plate 14 and the bend 14e offer an easy entrance for the fascia plate. Further, where this entrance is obstructed by sand, plaster or dust falling from the masonry, no difficulty is presented to fit the fascia plate, as any pointed tool such as a screw driver or scraper may be run across the assembly of the plate sections 14b and 14d to 100 clear the same of the deposit and permit the 105 springing of the section 14d and the insertion 110 of the fascia plate. In this connection, should any sand or dust fall into the cavity of the sections 14b and 14d, it would simply 115 drop to the spacious bottom of this cavity and be out of the way of the advancing fascia plate, saving time, labor and difficulty in fitting the plate. Further, the solid front presented by the header bend 10a enables the 120 plate 14 to be rigidly installed, so that it will not yield to the insertion of the fascia plate 11 and become warped or otherwise distorted. The plate 14 presents a solid backing for 125 the fascia plate, only the section 14d yielding when the plate is inserted. Further, the retainer molding 9d of the sill 9 presents an integral expedient for receiving and holding the fascia plate against the sill, the auxiliary fastening by the screws 16 being simply 130 to prevent the downward creeping of the plate. Further, the peculiar relation of the sill and retainer plate formations permits me to provide a fascia plate which need not be accurately dimensioned as to height; it suffices if the plate is only generally of a suit-

able dimension to be received within the retainer plate and the sill molding, to be shifted as desired for the fitting of the screws 16, the elongated slots 11a in the plate giving the latter sufficient play to adjust the plate to inaccuracies in the lateral spacing of the tapped bores 9c in the sill.

In the modification of Figures 3, 5, 7 and 8 special provision is made for the fascia plate at the upper end of the elevator shaft, since no sill is there available to furnish a support. Accordingly, the fascia plate 11 proper is only made of partial height and terminated at the top with an obtuse bend 11b in the direction of the main masonry front 6. The bend 11b overlies an extension plate 17 which rises to meet the masonry as clearly shown in Figure 5. The bend 11b is made with a longitudinal series 13 of countersunk perforations 11c through which screws 18 pass to thread into tapped bores 17a in the plate 17 located to correspond. The fascia and extension plates are drilled together and assembled temporarily by means of the screws 18 before the plates are installed on the job. When this is done, the screws are advanced until the extension plate is drawn up whereby to reduce its slope and cause it to bear firmly 25 against the masonry. In order that shock or injury to the joined plates may not dislodge the fascia plate from its retaining elements 14, 14e, I secure two pendent spring hooks 19 on the frontal side of the fascia plate by screws 20, snapping the hooks over the bead 14e of the retainer structure. This expedient will prevent the fascia plate from being pulled out of the retainer. Yet, the hooks are invisible from the shaft; the screws 20 are 30 outside the cab-opening lines, as indicated by dotted lines in Figure 3; and the screw heads 18 are above the traveling limit of the elevator cab and therefore invisible. The installation just described thus lends the fascia plate a smooth top termination.

In the modification of Figures 4 and 6, special provision is made to adapt the fascia plate to the bottom of the elevator shaft. In this case, the fascia plate, as secured in the sill 9, is terminated part-way down with an obtuse bend 11d directed toward the advanced masonry layer 5. Inside the bend 11d is applied an extension plate 21, which drops inclinedly to meet the masonry front. The bend 11d and the extension plate 21 are connected and applied by the same method and means as the corresponding parts at the upper end of the elevator shaft—namely, the bend 11c and the extension plate 17—the bend perforations at the lower site being denoted by 11e, the screws by 22, and the tapped bores by 21a. The fascia plate is thus neatly extended to form a bottom terminal.

In conclusion, it will be seen that the ma-

terial employed in the novel covering is of simple and sturdy design and of a nature to be durable for long periods without frequent attention or repair.

I claim:

1. A fascia plate installation for elevator shafts, comprising a door-sill extension opposite the upper portion of the fascia plate, said extension being recessed to receive such portion.

2. A fascia plate installation for elevator shafts, comprising a door-sill extension opposite the upper portion of the fascia plate, said extension being slotted from the bottom to receive such portion to any depth of the slot.

3. A fascia plate installation for elevator shafts, comprising a frontal door-sill extension to receive and retain the upper portion of the fascia plate, and a downward extension of the door sill and serving as a backing for said portion.

4. The structure of claim 3, said portion being made with perforations, and fascia plate fastening means secured in the downward extension by way of said perforations.

5. The structure of claim 3, said downward extension being made with tapped bores and said portion being made with slots having extended registration with corresponding ones of the tapped bores, and screws advanced into the latter by way of said slots to fasten the fascia plate to said downward extension.

6. A fascia plate support comprising bearings to slidably receive the upper and lower portions of the fascia plate, and means to fasten the plate to any height of its adjustment.

7. The structure of claim 6, and a pressure element frictionally engaging the fascia plate in one of the bearings.

8. A retainer for a fascia plate comprising a header front mounting to which the fascia plate is applicable from behind, and pressure means engaging the back of the plate to urge the latter against the mounting.

9. A retainer for a fascia plate comprising an upstanding header front, an inverted U-mounting fitted over the header front and to which the fascia plate is applicable from behind, and a spring pressure clip carried by the mounting and engaging the back of the plate to urge the latter against the mounting.

10. A retainer for a fascia plate comprising an upstanding header front, an inverted U-mounting fitted over the header front and to which the fascia plate is applicable from behind, a rearward base extended from the rear section of the U-mounting, and a forward compression clip extended from the base and engaging the back of the plate to urge the latter against the mounting.

11. A retainer for a fascia plate comprising a horizontal header with an upstanding

front, an inverted U-mounting fitted over the header front and to which the fascia plate is applicable from behind, a rearward base extended from the rear section of the U-mounting, fastening means securing the base to the header, and a forward compression clip extended from the base and engaging the back of the plate to urge the latter against the mounting.

12. A fascia plate installation for an elevator shaft containing a door-hanger compartment, comprising a top header for the latter and having an upstanding front, a mounting secured upon the front and receiving the fascia plate from behind, a downward extension of the mounting and inwardly formed with a receptacle, and a frontal lid for the compartment formed with a top inverted U-hook to engage said receptacle and receive a support therefrom.

13. In an elevator shaft installation a connecting medium between a fascia plate and the frontal door-hanger compartment lid below, comprising a clip formed with jaws between which the fascia plate is receivable, a forward extension of one of the clip jaws of inverted U-form, a downward continuation of said extension, a receptacle formed at the lower end of the continuation, and an inverted U-hook formed at the top of the lid to engage the receptacle.

14. A fascia plate applicable to the sill of an elevator shaft division and means applicable by way of the plate to fasten the latter to the sill, said means being situated outside the lateral limits of the passage-opening of the cab traveling in said division.

15. A fascia plate terminal for an elevator shaft in which the corresponding wall is set back from the fascia plate, comprising an extension of the plate in the direction of and to meet the wall.

16. The structure of claim 15, and tension means to urge the extension in constant engagement with the wall along its meeting area with the latter.

17. A fascia plate terminal for an elevator shaft in which the corresponding wall is set back from the fascia plate, comprising a terminal bend of the plate in the direction of the wall, an extension plate applied to the bend and inclinedly projected to meet the wall, and fastening means at the meeting site of the bend with the extension plate and adjustable to draw on the latter with the effect of urging the extension plate firmly against the wall along its meeting area with the latter.

18. Fascia plate retaining means comprising a clip between whose jaws the fascia plate is receivable, one of said jaws having an outward enlargement, a hook extending from the fascia plate and engaging said enlargement, and means fastening the base of the hook to the fascia plate.

19. The structure of claim 18, said hook

being tensioned to maintain its engagement.

20. A fascia plate installation for elevator shafts, comprising a door-sill extension opposite the upper portion of the fascia plate, said extension receiving such portion.

21. A fascia plate support comprising bearings to slidably receive the upper and lower portions of the fascia plate.

22. The structure of claim 8, said pressure means comprising a spring clip.

23. A retainer for a fascia plate comprising a substantially horizontal header plate, an upstanding member disposed frontally thereof and to which the fascia plate is applicable from behind, and pressure means engaging the back of the fascia plate to urge it against said member.

24. A retainer for a fascia plate comprising a substantially horizontal header plate, formed with an upstanding front, an inverted U-mounting fitted over the header front and to which the fascia plate is applicable from behind, a rearward base extended from the rear section of the U-mounting, fastening means securing the base and rear section, and a forward compression clip extended from the base and engaging the back of the plate to urge the latter against the mounting.

25. A fascia plate applicable to the sill of an elevator shaft division and means applicable by way of the plate to fasten the latter to the sill, said means permitting lateral play for the adjustment of the plate before it is fastened.

26. Fascia plate retaining means comprising a clip between whose jaws the fascia plate is receivable, one of said jaws having an outward enlargement, and a clamping element extending from the fascia plate and engaging said enlargement.

27. The structure of claim 12, an inward extension of the mounting in immediate contact with the fascia plate, and means securing the extension to the header.

28. The structure of claim 12, an inward extension of the mounting in immediate contact with the fascia plate, and means securing the extension to the header, said means being concealed by said downward extension from the elevator shaft.

29. A saddle with an edge adapted to project into an elevator wall, a recessed under surface at said edge adapted to receive a cover plate and means on said edge for receiving a fastening for securing the cover plate in place.

In testimony whereof I affix my signature.
THOMAS J. OSINGA.
